UNITED STATES PATENT OFFICE

153,279

DESIGN FOR A SHIRT

William E. Gluskin, New York, N. Y.

Application July 3, 1948, Serial No. 147,378

Term of patent 3½ years

(Cl. D3—25)

To all whom it may concern:

Be it known that I, William E. Gluskin, a citizen of the United States, residing in the county of Queens, city and State of New York, have invented a new, original, and ornamental Design for a Shirt, of which the following is a specification, reference being made to the accompanying drawing, forming a part thereof.

In the drawing:

Fig. 1 is a front elevational view of a shirt, showing my new design;

Fig. 2 is a back view thereof; and

Fig. 3 is a view similar to Fig. 1, showing the shirt in open position.

I claim:

The ornamental design for a shirt, as shown.
WILLIAM E. GLUSKIN.
